UNITED STATES PATENT OFFICE.

WILLIAM W. HARRIS, OF NEWPORT, NEW JERSEY.

MULTIPLE-UNIT GAS-GENERATING SYSTEM.

Application filed February 11, 1922. Serial No. 535,842.

To all whom it may concern:

Be it known that I, WILLIAM W. HARRIS, a citizen of the United States of America, residing at Newport, county of Cumberland, 5 State of New Jersey, have invented certain new and useful Improvements in Multiple-Unit Gas-Generating Systems, of which the following is a specification.

This invention relates to multiple unit gas 10 generating systems comprising a plurality of generators, each generator having its individual carbid supply, water supply and generating chamber and a common service pipe interconnecting such units. 15 An object of the invention is to provide a generating system comprising two or more individual generating units each constructed to receive separate masses of carbid and water and interconnected in a manner whereby 20 upon withdrawal of acetylene through the common service pipe the further generation of the acetylene is effected combinedly in separate generating chambers. Such arrangement affords advantages during the 25 stage of generation of acetylene by reason of the distributed masses of the water within the several containers, thereby enhancing the dissipation through a relatively smaller body of water of the heat generated upon the 30 production of acetylene, and further by the increased radiating surface of the exposed outer walls of the containers, usually of iron or similar metal.

In accordance with a preferred form of 35 the invention, each unit is of the substantially constant pressure type, wherein the carbid is charged in an upper carbid container, and fed under the control of a non-friction feeding mechanism to the water disposed 40 in a lower water container, such feeding mechanism being actuated by a diaphragm in turn actuated by changes of volume of the acetylene accumulated within each unit, and resilient means for 45 each unit for controlling the sensitiveness of its diaphragm and adjustable means for regulating such resilient means. Such two or more units may be arranged as a bank and interconnected by passages for conducting 50 the acetylene respectively from the several units to a common discharge means.

Pursuant to my invention, the generation of the required amount of acetylene is carried out by means of a number of units 55 which may be disconnected from one another when it is desired to transport the

same, whereby the lesser weight of each unit individually facilitates the removal of the bank as a whole. I have also discovered that the generation of acetylene by the respective units combinedly affords improved maintenance of pressure of the gas supplied to the service pipe. 60

Further features and objects of the invention will be more fully understood from the following detail description and the accompanying drawings, in which—

Fig. 1 is a front elevation of a bank of two acetylene units constructed and arranged in accordance with my invention; 70

Fig. 2 is an end elevation of the arrangement shown in Fig. 1 and also indicating the path of movement of one of the carbid containers to its re-charging position and the path of movement of one of the water containers for discharging the sludge; 75

Fig. 3 is a detail vertical sectional elevation, on an enlarged scale, taken on line 3—3 of Fig. 1;

Fig. 4 is a detail vertical central elevation, 80 showing the conjoint discharge arrangement, on an enlarged scale, taken on line 4—4 of Fig. 2;

Fig. 5 is a detail vertical section, showing on an enlarged scale the feeding portion of 85 a plunger, taken on line 5—5 of Fig. 3;

Fig. 6 is a perspective view of a carrier for a bank of two units, as shown in Fig. 1; and

Fig. 7 is a detail vertical central sectional view through the upper portion of a water container, showing an improved sludge discharge and water refilling means, comprising a float attachment for indicating the water level. 90

Referring to Fig. 1, the generator is shown of two units 10, 11; it will be understood that in a similar manner, three or more units may be arranged and interconnected with one another for the combined generation of acetylene. 100

The various operating parts of the different units are preferably of the same arrangement and approximately of the same dimensions, and in the following description, specific reference will be had to one unit and the corresponding parts of the other unit are designated by the same reference characters. 105

In the preferred form, as shown in the drawings, the carbid container 12 is disposed above the water container 13. The 110

bottom of each water container is usually designed to afford proper support for the unit as a whole on the floor or in a common carrier frame 14, described more specifically hereinafter.

Referring to Fig. 3, the carbide container 12 is provided at its lower end with the opening 15, having the valve 16, through the orifice 17 of which extends the feeding portion 18 of the plunger 19. The plunger 19 is secured to the diaphragm 20 of rubber composition, rubber fabric or the like. The hopper 12 may be of cylindrical contour and in such instance, the diaphragm 20 may be circular and be secured to the hopper 12 by clamping the peripheral portion 21 of the diaphragm 20 to the upper, laterally extending flange 22 of the hopper 12. Centrally, the diaphragm 20 is recessed to receive the connecting piece 22, the lower face of which is screw-threaded to adjustably receive the upper threaded end 23 of the plunger 19. The plunger 19 may be locked in its adjusted position by means of the lock nut 24. Usually, the diaphragm 20 is secured to the connecting piece 22 by suitable clamps, such as the clamp disk 25 and the lock nut 26.

The connecting piece 22 is provided with an upward tubular portion within which is received the stem 27 extending exteriorly at 28 through the upper end of the casing 29. The lower end of the stem 27 is secured to the tubular extension by means of the peripheral circular slot 30 within which extends the locating set screw 31, screw-threadedly held within a suitable opening in the tubular extension. The upper portion 32 of the stem 27 is provided with screw-threading for meshing with the inner screw-threading of the nut carrier 33, about which is secured the upper converging end 34 of the coiled spring 35. The lower end 36 of the coiled spring 35 is rotatably held within the cup ring 37.

The casing 29 may be secured to the domed top plate 40 of the carbide hopper 12 by means of the ring extension 41, the inner face of which is threaded at 42 to receive the threaded lower end of the casing 29. The retaining ring 37 is locked in position relative to the carbide hopper 12, i. e., to the domed top 40 of the carbide hopper 12, by engagement therewith of the lower edge 55 of the casing 29 when fully seated within the ring extension 41.

The upper end of the casing 29 may be closed by means of the threaded cap 43 having the central opening 44 through which extends the end 28 of the stem 27; pivotally secured in a slot in the end 28 of the stem 27 is the cam lever 45, generally of an L-shaped contour; the pivot 46 being located near one extremity of the same. The face 47 of the cam lever 45, appearing

in Fig. 3 as lowerly in position, may be flattened, whereby when the lever 45 is moved to the position shown in full outline in Fig. 3, the lever 45 is in stable engagement with the upper face of the cap 43. The edge 70 portion 48 of the cam lever 45, is circular or of other curvature, thereby facilitating the cam action of the lever 45 to raise the stem 27 and therewith the plunger 19, to lock the feeding mechanism 18 in its non-feeding position, at which stage the cam lever 45 is in the position shown in full outline in Fig. 3.

Such arrangement of the stem 27 and its co-ordinated parts, affords turning of the stem 27 by means of the lever 45, whereby upon clockwise rotation of the lever 45, as viewed when looking down in Fig. 3, the stem 27, having a right-hand thread as illustrated, causes the supporting nut 33 to rise, thereby elevating the upper end 34 of the spring 35, which by reason of the lodgement of the lower end 36 of the spring 35 within the ring 37, the spring 35 will be distended and the tension asserted by the spring 35 through the stem 37 upon the diaphragm 20 exerts a downward pressure. Thus upon raising the supporting nut 33 of the spring 35, the downward pressure on the diaphragm 20 may be increased as desired. Similarly, upon turning the lever 45 in a counter-clockwise rotation, as viewed downwardly in Fig. 3, the nut 33 will be lowered and the pressure of the spring 35 on the diaphragm 20 will be lessened.

The cam lever 45 is provided with the retaining notch 49, see Fig. 2, on its edge 49^a, see Fig. 3, for automatically retaining the lever 45 in its raised or locked position. Upon raising the lever 45 from its full line position indicated in Fig. 3, its edge 49^a rides over the circular edge of the cap 43 during normal reciprocations of the feed mechanism; however, in the event of abnormal pressure of the accumulated gas by which the stem 27 is carried to its uppermost position the cam lever 45 will assume the position 45^a shown in dash outline, its notch 49 becoming lodged on the edge of the cap 43, whereupon the feeding mechanism of such unit is locked in its non-operative position.

Preferably, the feeding mechanism 18, for controlling the delivery of the carbide from the carbide hopper into the water reservoir 13, embodies the self-yielding features set forth and claimed in my copending application Serial No. 531,557 filed January 25th, 1922. In the construction shown in Figs. 3 and 5, the feeding mechanism comprises the stud 50 connected by its threaded end 51 to the lower end of the plunger 19; also the enlargement 52, relatively fixedly connected at the lower end of the plate 53, the upper end of which is connected to the stud 50.

The plate 53 yieldingly carries the coiled spring 54, as by passing the convolutions of the coiled spring 54 through the staggered sets of openings 55, the diameter of such openings 55 being larger than the cross-sectional area of the wire of the coil 54. Accordingly, upon the plunger 19 being free to be moved under action of the diaphragm 20, in which stage the lever 45 is in its un-

10 locking position, the plunger 19 descends until the coil 54 moves downwardly through the feed opening 17 of the valve seat 16, thereby controlling the discharge of carbid granules through the orifice 17. The feed

15 of the carbid into the water in the water receptacle 13 gives rise to generation of acetylene which passes upwardly through the feed orifice 17, through the charge of carbid granules to the upper portion of

20 the carbid hopper 12 and actuates the diaphragm 20 by reason of changes of volume of the gas, and in turn actuating the feeding mechanism 18.

The gas generated in any unit is discharged therefrom through its outlet 60 communicating with the interior of the unit at any suitable location, such as the location 61, see Fig. 2, leading into the outer casing 62, see also Fig. 3; the outlet 61 may 30 be connected by a yieldable piping 63 to the nipple 64, see Fig. 4.

Preferably, the carbid hopper 12 is hingedly mounted relative to the water reservoir 13, as by means of the strap 65, 35 see Figs. 2 and 3, suitably secured to the outer casing 62 of the carbid hopper; the strap 65 is secured by the pin 66 to the arm 67 having a squared end face to permit limited movement of the hopper to self-adjust itself when being clamped to its water container, as described more fully hereinafter.

The arm 67 is hinged to the tapered plug 68 screw-threaded in the double yoke 69, 45 by means of a conical fitting and retained by the set-screw 71 passing through a suitable opening in one end on the clamping arm 72, the opposite end 73 being secured to the plug 68 in any suitable manner.

50 The plug 68 is provided with the central passage 68^a, leading the gas from the orifice of the nipple 64 to the pipe 74. The respective pipings 74, 74 lead to the common discharge chamber 75 of the bank of units, 55 as by means of the T-nipple 76 communicating at its opening 77 with the chamber 75. Preferably, the chamber 75 contains a washing fluid 78. The ball valve 79 is provided at the outlet 77 to prevent back-pressure as when the system is used in combination with other gases compressed to higher pressures. Such valve 79 serves also to prevent back-fire.

60 The chamber 75 is provided with the filling plug 80 and the drain plug 81. The re-

spective pipes 74 are equipped with the valves 82 for turning off and turning on the flow of acetylene therethrough from the individual units. Preferably, the discharge chamber 75 contains also a dehydrating or filtering medium 83 supported by the reticulated bottom 84. The discharge chamber 75 may be closed by means of the closure plug 86 locked by the hinge yoke 87 and the set screw 88. As appears in Fig. 75 2, the service pipe 89 leads from the top of the discharge chamber 75 and the pressure gauge 90 is provided for indicating the pressure of the discharging gas.

Preferably, the bottom flange 91, see Fig. 3 of the carbid hopper is concaved to receive a suitable gasket 92, see Fig. 7, carried within the concaved flange 93 of the neck portion 94 of the water reservoir 13 and the lower flange 91 of the carbid hopper is locked in sealing relation with the upper flange 93 of the water reservoir 19 by means of the oppositely disposed cam hooks 95, see Fig. 2 operated by the common lever handle 96. The lever handle 96 may serve as a bail of the water reservoir 13, when desired.

When it is desired to recharge the carbid hopper 12 the handle 96 is raised, to thereby raise the cam locks 95 from engagement with the extensions 99 respectively of the strap 65, whereupon the carbid hopper 12 may be swung on the arm 67 and inverted to the position 12^a shown in dash-outline in Fig. 2. To facilitate charging carbid into the carbid hopper, the valve seat 16 is provided with the exterior portion 100 see Fig. 3, which may be removed by unscrewing the same. The carbid is then fed through the enlarged opening of the orifice, past the abutment 52 and valve feeding portion 18 of the plunger 19.

The sludge may be removed from the water reservoir 13 by tilting the water reservoir and to facilitate such action by manual operation, I have provided suitable means associated with the carrier 14 as is described more particularly hereinafter.

The removal of the sludge and refilling with fresh water is facilitated by means of the attachment 101, see Figs. 7 and 2, constructed to be attached to the top flange 93 of the water reservoir 13 by means of the cam locks 95, by similar operation of the curved lever handle 96. The attachment 101 is thus seated in liquid tight engagement with the upper flange 93 of the water reservoir by means of the gasket 92. Such attachment 101, provides for ready discharge of the sludge and the protection of the gasket 92 and mouth 93 of the water receptacle 13, to prevent fouling, and also serves as a funnel when re-charging the reservoir 13 with water.

65 To facilitate indication of a proper

amount of fresh water supplied to the water reservoir, I provide the level indicator 103 secured to the inner face of the attachment 101 and comprising the bracket 104 having suitable openings in its opposite arms loosely receiving the rod 105, at the lower end of which is attached the body float 106. The rod 105 is provided with the stop 107 at its upper end to limit the downward movement of the float rod 105. As the water poured into the water reservoir 13 reaches approximately the level indicated at 108, the float 106 becomes operative and the movement of the stop 107 relative to the bracket 104 shows the operator when the proper level has been reached.

Upon properly charging carbid into the individual carbid holders and water into the respective water reservoirs, and releasing the levers 45 from locking position, the carbid feeding mechanisms of the respective units are actuated by the combined action of their diaphragms and regulating springs, and the generation of gas ensues for all the units connected in with the common discharge outlet. It will be noted that the two or more units when their cocks are turned on, are connected with one another through common passage ways, thereby affording equalization of pressure within the interiors of the different units. When it is desired that each unit operate to the same degree of output, the reciprocation of the plungers is observed and the more slowly operating unit or units are increased in tension of their regulating springs, or the faster unit or units reduced in tension of their regulating springs, until all units of the system operate in unison. During such simultaneous operation of the carbid feeding mechanism of the respective generators the carbid is delivered from any carbid hopper to its water reservoir in the amount corresponding to the extent of gas furnished by such unit and a substantial constant pressure is maintained simultaneously within the interiors of the respective units. By reason of the relatively lesser mass of water in any single water reservoir, the heat derived by exothermic chemical reaction of carbid with water is readily conducted through the mass of water and dissipated at the exposed face of the circular or other side walls of the water receptacle. It will also be noted that by reason of the water being distributed within a number of units, the surface of the water receptacles give rise to a marked dissipation of the total heat evolved in the chemical reaction. Upon any unit approaching its fully discharged condition, its cock 82 may be closed and the unit re-charged while the remaining unit or units are continued in use.

The combined generator units form a bank which may be when desired, disconnected from one another, to afford individual trans-

portation, which advantage is of importance in many uses of acetylene.

The transportation of two or more units and as a bank may also be carried out by means of a common carrier such as has been indicated generally hereinabove. The frame 14 shown in perspective in Fig. 6 and in assembly with two units in Fig. 1, may comprise the bottom rectangular frame 110 which may be braced by the one or more transverse straps 111. At the locations in the carrier for receiving the water reservoirs, in this instance two water reservoirs, I provide the double U-brackets having two vertically extending arms 112 having slots 113 at their upper extremities for receiving the oppositely extending ends 114 of the bar 115, see Figs. 1 and 2. The bar 115 may be secured to one side of the water generator 13 by any suitable form of brackets 116. The brackets 112 are pivoted at their opposite ends 117 in the bearings 118, secured to the bottom frame 110 of the carrier 14. The double U brackets comprise further the members 119 connected as pairs by the cross piece 120, for receiving and supporting the bottom of a water reservoir 13. Thus, upon manually tilting over a water reservoir 13, as is indicated in Fig. 2, the double U-bracket including the arms 112 and the arms 119 are rotated clockwise, as viewed in Fig. 2, say to the limiting position indicated by dotted outline, namely, by the ends of the arm 119 striking the bar 121, whereafter the water reservoir 13 may be further tilted on its bar 115 to its final emptying position shown by dot and dash outline.

Whereas I have described my invention by reference to specific forms thereof, it will be understood that many changes and modifications may be made without departing from the spirit of the invention, as defined by the appended claims.

I claim:

1. In an acetylene supply system, the combination of a plurality of generating units, each of said units including carbid feeding means automatically responsive to changes in the pressure of the gas accumulated within said units and means for adjusting said carbid feeding passage means respectively, a common service outlet means for pivotally mounting said carbid feeding means respectively to said common service outlet, means for interconnecting said units with said common service outlet and means coacting with said adjusting means respectively for locking the respective carbid feeding means in closed position.

2. In an acetylene supply system, the combination of a plurality of generating units, each generating unit comprising carbid feeding means, a carbid container and a separate water container, a common service outlet, means for pivotally supporting 130

said carbid feeding means respectively on said common service outlet, adjusting means for controlling the operation of said carbid feeding means in unison and means coacting with said adjusting means for locking said carbid means in closed position.

3. In an acetylene supply system, the combination of a plurality of generating units, each generating unit comprising carbid feeding means, a carbid container and a separate water container, a common service outlet, means for pivotally supporting said carbid containers respectively on said common service outlet, adjusting means for controlling the operation of said carbid feeding means, means for disconnecting any of said units from said common service outlet and means coacting with said adjusting means for locking the carbid feeding means of such disconnected unit in closed position.

4. In an acetylene supply system, a plurality of generating units, each unit having separate carbid and water containers, means for removably mounting the carbid container of any unit on its water container, and means for discontinuing the operation of said units respectively, a common service outlet, means for interconnecting said units with said common service outlet, a common carrier for said generating units, and means mounted on said carrier for respectively mounting the water containers of said units to respectively tilt the same to discharge the sludge therefrom.

35 5. In an acetylene supply system, the combination of a plurality of generating units, a common carrier for said generating units, each generating unit including a carbid container and a separate water container, means carried by said carrier for holding said carbid container in re-charging position, a common service outlet supported by said common carrier, means including individual gas conveying members for the respective units interconnecting said units with said common service outlet and means coacting with said individual gas conveying members for hingedly mounting the respective carbid containers on the water containers.

50 6. In an acetylene supply system, the combination of a plurality of generating units, a common carrier for said generating units, each generating unit including a carbid container and a separate water container, means for hingedly mounting each carbid container on its water container to permit removal of the carbid container for re-charging, means carried by said carrier for holding said carbid container in re-charging position, a common service outlet supported by said common carrier, means including individual gas passages for the respective units interconnecting said units with said common service outlet, and means hingedly mounted on said common carrier for respec-

tively tilting the water containers to emptying position.

7. In an acetylene supply system, a plurality of generating units, each unit having separate carbid and water containers, means for removably mounting the carbid container of any unit on its water container, and means for discontinuing the operation of said units respectively, a common service outlet, means for interconnecting said units with said common service outlet, a common carrier for said generating units and means carried by said carrier for holding the respective carbid containers in disconnected relation with their water container respectively to permit re-charging with carbid.

8. In an acetylene generating system, a generating unit comprising a carbid container, a water container, means for removably mounting said carbid container on said water container, means including locks for holding said carbid container in sealing relation with an end face of the discharging opening of the water container, means coacting with said locks for attachment to the discharging opening of said water container for discharging the sludge free from said sealing end face of said discharge opening and for receiving the re-charged water free from said sealing end face.

9. In an acetylene generating system, a generating unit comprising a carbid container, a water container, means for removably mounting said carbid container on said water container, a plurality of cam locks for holding said carbid container in sealing relation with an end face of the discharging opening of the water container, common means for operating said plurality of locks, means coacting with said locks for attachment to the discharging opening of said water container for discharging the sludge free from said sealing end face of said discharge opening and for receiving the re-charged water free from said sealing end face.

10. In an acetylene generating system, a generating unit comprising a carbid container, a water container, means for removably mounting said carbid container on said water container, a plurality of locks for holding said carbid container in sealing relation with an end face of the discharging opening of the water container, common means for operating said plurality of locks, means coacting with said locks for attachment to the discharging opening of said water container for discharging the sludge free from said sealing end face of said discharge opening and for receiving the re-charged water free from said sealing end face and means secured to said attachment means for indicating the level of the water re-charged in said water container.

11. In an acetylene generating system, a

generating unit comprising a carbid container, a water container, means for removably mounting said carbid container, on said water container, a plurality of cam locks for holding said carbid container in sealing relation with an end face of the discharging opening of the water container, common means for operating said plurality of cam locks, means coacting with said locks for attachment to the discharging opening

of said water container for discharging the sludge free from said sealing end face of said discharge opening and for receiving the re-charged water free from said sealing end face and means secured to said attachment means for indicating the level of the water re-charged in said water container. 15

In testimony whereof I have signed this specification this 8th day of February, 1922.

WILLIAM W. HARRIS.
